US0D1058103S

(12) United States Design Patent (10) Patent No.: US D1,058,103 S
O'Sullivan (45) Date of Patent: * Jan. 21, 2025

(54) APPAREL

- (71) Applicant: Reebok International Limited, Altrincham (GB)
- (72) Inventor: Patrick O'Sullivan, Cambridge, MA (US)
- (73) Assignee: Reebok International Limited, Altrincham (GB)
- () Term: 15 Years
- (21) Appl. No.: 29/783,117
- (22) Filed: May 11, 2021

Related U.S. Application Data

- (62) Division of application No. 29/681,179, filed on Feb. 22, 2019, now Pat. No. Des. 920,630.

Primary Examiner — Michelle E. Wilson*Assistant Examiner* — Clese Moore, Jr.(74) Attorney, Agent, or Firm — Sterne, Kessler, Goldstein & Fox P.L.L.C.(57) CLAIM

The ornamental design for apparel as shown and described.

DESCRIPTION

FIG. 1 is a front view of apparel showing the claimed design; FIG. 2 is a rear view thereof; FIG. 3 is a left side view thereof; FIG. 4 is a front view of a second embodiment of apparel showing the claimed design; FIG. 5 is a rear view thereof; and, FIG. 6 is a left side view thereof.

The dashed broken lines in the figures show portions of the apparel that form no part of the claimed design.

The dot-dash broken lines in the figures show boundaries that form no part of the claimed design.

The figures are illustrated to show contrasting appearance. The gray-shaded portions of the apparel have one appearance and the white or black claimed portions have a different appearance.
